UNITED STATES PATENT OFFICE.

HAL G. BAKER AND JOHN R. MOORE, OF SPRINGFIELD, ILLINOIS.

BOTTLE HOLDER.

Application filed July 27, 1926. Serial No. 125,193.

Our invention relates to bottle holders of the type in which a bottle held in one container is secured in such manner that it is necessary to place another bottle in the other 5 container before the first named bottle can be removed.

The purposes of the invention are: to provide containers of improved construction; to provide improved means controlling the 10 insertion of bottles into the containers and their removal therefrom; and to provide an improved latch unit comprising a sheet metal base formed from a single sheet-metal blank, and co-operating right and left latch levers 15 supported on said base.

We attain these purposes by the means illustrated in the accompanying drawings in which: Figure 1 is a front view of a bottle holder embodying our invention; Fig. 2 20 is a vertical section through the casing and one container, taken on the line 2-2 of Fig. 1; Fig. 3 is an enlarged top view of the bottle holder; Fig. 4 is a vertical section taken on the line 4-4 of Fig. 3 and 25 showing a bottle in one container; Fig. 5 is an enlarged top view of the detached latch-unit; Fig. 6 is a partial vertical section through the latch-unit taken on the line 6-6 of Fig. 5; Fig. 7 is a vertical section 30 taken on the line 7-7 of Fig. 5; Fig. 8 is a top view of the sheet metal blank from which the base of the latch-unit is formed.

Similar reference numerals and letters designate similar parts throughout the several 35 views.

The principal elements of the mechanism are: a rectangular sheet metal casing 9; a centrally placed vertical partition 10 dividing the casing into two equal compartments 12 and 12'; and two containers R and L, one in each compartment, hinged on a horizontal rod 13 extending the full width of the casing; and one latch-unit, designated as a whole by the numeral 14, to be described 45 in detail later.

The containers R and L are alike except that one is right and the other left, so a description of one will suffice for both. The container R is of sheet metal and comprises 50 a front wall 15, two side walls 17 and a floor 18. In the front wall is a hole 16 to receive the finger of a hand used to open the container. In the floor 18 is an opening 19 to accommodate an upwardly ex-

tending finger 32 which is part of the latch 55 mechanism. A perforation 45 in one side wall is in range with the slot 20 in the partition 10 when the container is closed. On the upper edge of each side wall is an upwardly extending member 29 which strikes 60 against a stationary stop 46 on the casing 9 to limit outward turning of the container on the hinge rod 13.

There are two similar angular latch levers 22 and 30 one right and the other left. 65 Different numerals are used on the different levers in order to describe clearly the manner of co-operation of the levers.

The left hand latch-lever designated as a whole by the numeral 22 comprises an 70 approximately horizontal member 23 having an upwardly extending finger 24; an upright member 25 having an integral wedge-shape extension 26 (Fig. 4) and a hook-member 27. The right hand latch-lever, 75 designated as a whole by the numeral 30, comprises an approximately horizontal member 31 having an upwardly extending finger 32; and an upright member 33 having a wedge shape extension 34 and a hook 80 member 35.

The base of the latch-unit 14 is formed from a sheet metal blank B shown in Fig. 8.

The blank B comprises two members b, each having a perforation b¹; two members b², each having a lengthwise slot b³ and two members b⁴ each having a hole b⁵. The members b are bent upward along the lines b⁶ to form the ears 36. The ears are secured 90 on the partition 10 by screws 39, (Fig. 3) extending through the holes b¹. The members b² are bent upward along the lines b⁸ to form the slotted upright guides 38. The members b⁴ are bent upward along the lines b⁷ to form the standards 37. A bolt 40 extends through the standards and through the angular levers 22 and 30 and the levers oscillate on the bolt. The holes b¹ and b⁵ and the slots b³ will be punched in the blank before bending. 95

The slots b³ guide upward and downward movement of the lever-members 23 and 31. A wire spring 41 coiled around the bolt 40 has members 42 and 43 which hook under the respective lever-members 23 and 31. 105 Weight applied on the fingers 24 and 32 serves to stress the respective spring members and the spring members act to raise

the respective lever members 23 and 31 as the case may be when the weight has been removed.

When the parts have been assembled as shown in Figs. 3 and 4 the bottle holder will be in condition for use.

Operation.

When the parts are in the position shown in Fig. 6 both of the levers 22 and 30 will be neutral.

Assume that a full bottle has been taken out of the container L and an empty bottle C left therein and the container closed. The weight of the bottle will depress the finger 24 at the outer end of the member 23 to bring the lever 22 into position clearly shown in Fig. 4; to cause the extension 26 to project through the perforation 44 in the side wall 28 of the container L adjacent to the partition 10, thereby retracting the hook 27 from the perforation 45 in the side wall of the container R to permit the container R to be opened. The left hand container will then be locked and the right hand container will be unlocked and the spring member 43 will hold the member 31 in its raised position with its finger 32 extending upward through the hole 19 in the bottom 18 of the container R.

When the milkman comes to deliver the milk, he will open the right hand container and place a full bottle C' therein, and will then close that container.

The weight of the inserted full bottle in the closed container R will press the finger 32 downward to depress the member 31, resulting in stressing the spring member 43 and retracting the hook 35, as already described, to unlock the container L. He will then open the container L and take out the empty bottle C; and thereupon the spring member 42 will act to raise the member 23 to cause the member 25 to move towards the right to retract the extension 26 from the perforation 44 and project the hook 27 into the perforation 45 so that upon closing the container L it will remain unlocked in readiness for the next operation, but the container R will remain securely locked until another bottle is placed in the container L.

A bottle placed in the container L engages and presses downward the member 24 of the lever 22 causing the member 27 to move toward the left out of the perforation 45 in the side wall of the container R, thereby unlocking it while the container L remains locked. At this stage the spring member 43 holds the member 31 of the lever 30 at the limit of its upward movement in the slot 7³ causing the hook member 35 to protrude through the perforation 44 in the side wall of the container L securely locking same; the container R being then empty and unlocked, the milkman will open the container and will

place a bottle of milk therein and will close the container; the closing of the container R will cause the filled bottle to press downward on the finger 32 thereby causing the member 35 of the lever 30 to move toward the right out of the perforation 44 in the side wall of the container L thereby unlocking that container. He will then open the container L and take out the empty bottle. Upon taking out the empty bottle and closing the container L, the spring member 42 will act to raise the member 23 to cause the member 24 to project upwardly through the hole 28 in readiness for the next operation. The raising of the member 23 will cause the member 27 to enter the perforation 45 in the side wall of the container R to lock that container, to protect the filled bottle.

The lower edges of the extensions 26 and 34 taper upwardly from the base to the point of the extensions; these inclined edges of the members permit them to slide on the lower edges of the perforations 44 or 45 while the containers are being turned outwardly on their hinges to open the containers.

The function of the members 26 and 34 is to prevent opening of the empty containers by releasing the hook 27 or 35, as the case may be, by a stick or other instrument operated by hand.

The upwardly extending lugs 29 on the side walls of the containers strike against a stationary stop 46 to limit outward turning of the containers. The act of opening an empty container brings the perforation 44 or 45 as the case may be, out of line with the extensions 26 or 34 as the case may be.

If the container R be opened as indicated in Fig. 2 and if the member 32 could then be pushed downward, the member 34 would strike against the side wall of the container R thereby preventing the withdrawal of the member 35 from the perforation 44 in the side wall of the container L, thereby keeping the container L securely locked.

The downward movement of the member 31 effects two results, 1st, it stresses the spring member 43; 2nd, it causes retraction of the hook 35 from the perforation 44 thereby unlocking the container L; and similarly the depressing of the member 23 results in stressing the spring member 42 and causes retraction of the hook 27 from the perforation 45 thereby unlocking the container R.

It is to be noted that the members 26 and 34 of the respective levers 22 and 30 incline upwardly from the base to the point, to enable the members always to clear the bottom edges of the perforations 44 or 45 as the case may be, while the containers are being opened. The perforations travel upwardly in the arcs of circles having their centers in the axis of the hinge-rod 13 as indicated at 45' in Fig. 2. When the perfora-

tion in the side wall of either container passes the point of the corresponding extension the side wall of the container will keep the extension retracted until the container 5 is closed again.

For example, the opening of the compartment R by hand brings the perforation 45 out of line relative to the extension 34, hence if it should be attempted to push the finger 10 32 downwardly by hand, or by a stick used in the container, the extension 34 engaging against the adjacent side wall of the container would prevent the retracting of the hook 35, thereby avoiding unlocking of the 15 container L.

When a bottle C is in the container L and the container is closed, the perforation 44 will be in range with the perforation 45 which will permit the extension 26 of the 20 lever 22 to enter the perforation 44 and will also permit the hook 35 on the lever 30 to enter the perforation 44.

At this stage there will be a bottle in each container; both members 23 and 31 will be 25 depressed and both spring members 43 and 42 will be stressed and both hooks 27 and 35 will be retracted, and either container may be opened and the bottle may be taken out of that container and upon closing that 30 container the proper hook 27 or 35 as the case may be, will engage in the proper perforation 44 or 45, as the case may be—to lock the other container.

In short when there is a bottle in a closed 35 container and the other container is empty, the closed container will be locked and the empty container will be unlocked; if the empty container be opened and a bottle placed therein and that container closed, 40 both containers will be unlocked and the removal of a bottle from either container will result in locking the other container.

So long as the containers L and R remain closed the upright members 25 and 33, of the 45 respective levers 22 and 30, are side by side in the lengthwise slot 20 in the partition 10; the openings 44 and 45 are in line with each other and the levers are free to oscillate left and right in the slot 20 and the extensions 50 26 and 34 are free to pass each other in the slot 20 to project the extension 26 through the opening 44, or to project the extension 34 through the opening 45, as the case may be.

When the hook 35 is retracted the wedge-shape extension 26 of the upright member 25 of the lever 22 will remain in the opening 44. The only function of the extension 26 is to obstruct the space between the bottle C 60 and the adjacent wall of the container L so that the hook 35 cannot be released by a stick or other instrument introduced into the container in an attempt to release the hook 35 which alone locks the container L; 65 and similarly the hook 27 near the upper

end of the upright member 25 of the opposite lever 22 is effective to lock the right hand compartment R. In short the right hand lever 30 alone controls the locking of the left-hand compartment and the left-hand lever 22 alone controls the locking of the right hand container. 70

The right hand spring member 43 (Figs. 5 and 6) actuates the lever 30 to cause the hook 35 to lock the container L and similarly the spring member 42 actuates the lever 22 to cause the hook 27 to lock the compartment R. 75

When bottles are in both containers both levers 22 and 30 are depressed; both spring members 42 and 43 are stressed; both containers are unlocked and either one may be opened and a bottle may be taken out with the result that the stressed spring under the compartment from which the bottle is taken 80 will act immediately to cause the locking of the opposite container. 85

Fig. 4 shows that the bottle shown by dotted lines in compartment R is above the upper end of the finger 32, and if the bottle 90 were pushed downward to the full extent it would depress the member 31 of the lever 30 (Figs. 5 and 6) to operate the member 33 to retract the hook 35 and stress the spring 43; at that stage both of the hooks 95 will be retracted and if the bottle C be removed the spring 42 will act immediately to raise the member 23 to actuate the member 25 to cause the hook 27 to engage in the 100 perforation 45, and lock the right hand container. 100

When there is a bottle in the container R and the container is completely closed the weight of the bottle on the upper end of the finger 32 will depress the member 31 to move 105 the member 33 to the right to cause the point of the extension 34 to enter the perforation 45 but that will not lock the container R. Both perforations 44 and 45 are of a sufficient width to allow extensions 26 or 34, as 110 the case may be, to clear each other as they move out of perforations 44 or 45 at the same time that the container R or L as the case may be; swings outwardly on the common axis 13. 115

When bottles are seated in both containers, either container may be opened, but both containers cannot be opened at the same time. The opening of one container automatically results in the locking of the other 120 container. 120

When the container R is opened as shown in Fig. 2, the point of the extension 26 will be in contact with the outer surface of the adjacent wall 17 and the container must be 125 completely closed before the member 34 can enter the perforation 45, and similarly the extension 26 cannot enter the perforation 44 until the container L is completely closed. In Figs. 3 and 4 the numeral 9 designates 130

the casing as a whole, the numeral 12 designates the left hand compartment of the casing and the numeral 12^a designates the right-hand compartment of the casing. The letter L designates the container in the compartment 12, and the letter R designates the container in the compartment 12^a.

Having fully described our invention, what we claim as new and desire to secure by 10 Letters Patent is:—

1. A bottle holder comprising a casing; a slotted partition dividing the casing into two compartments; duplicate hinged containers parallel to each other, one in each 15 compartment, each container consisting of a front member having a hole to receive the finger of a hand for turning the container outwardly on its hinge, two side members, one having a perforation in range with the 20 slot in the partition to receive a latch member when the container is closed, and a bottom member having an opening adapted to permit inward and outward movement of 25 latch-operating means, and latch levers oscillative on a common axis and adapted to traverse the slot in said partition, each lever having an extension adapted to extend through the slot in said partition and through a perforation in the wall of one container in range 30 with said slot, and a hook member engaging on an edge wall of the perforation in the opposite container to prevent outward turning of the engaged container.

2. A latch-unit for bottle holders comprising a base having upright standards and upright slotted guides; angular levers oscillative on a common axis supported on said standards and traveling in the slots in said guides and each having an extension and a hook near one end of the lever, and an upwardly extending finger at the other end of the lever; and a single spring acting upwardly on one member of each lever and effective to raise either lever independently 45 of the other.

3. A latch-unit comprising a base of sheet metal having upwardly extended standards; upwardly extended slotted members; upwardly extended ears perforated to receive means for connecting the latch-unit with a stationary element and angular levers oscillative on said standards and traveling in the slots in said guides; in combination with a casing having a vertical partition with 50 which said ears are connected; and two hinged containers, one on each side of said partition, said containers having perforations to receive members of said levers to lock the containers.

4. Latch mechanism comprising a pair of 60 angular levers oscillative on a common axis, each lever having a hook near one end and an upwardly extending finger at the other end; in combination with a pair of hinged containers parallel to each other, each container having in one side wall a perforation in range with said angular levers, said containers having openings to accommodate the upwardly extending fingers on the respective levers; a single spring stressed by a weight 70 applied on the finger of either lever and acting to retract the hook on the same lever from the perforation in the side wall of the opposite container to unlock the container opposite to that in which the weight is applied, and acting upon removal of the weight to return the lever to its original position and cause its hook to re-enter said perforation in the side wall of said first named container. 75

5. A bottle holder comprising a casing, a vertical slotted central partition dividing the casing into two compartments; two containers, one in each compartment; a hinged element extending across the front of each container at its lower edge; each container having in its side walls adjacent to said partition a perforation registerable with the slot in said partition and latches oscillative in the slot in said partition and engaging the adjacent side walls of the respective containers to lock the container in one compartment when a bottle is absent from the other container. 80

6. A bottle holder comprising a casing; 90 an upright partition dividing the casing into two compartments, said partition having a lengthwise slot; containers in the respective compartments; a hinge element connecting both containers at their respective lower front edges, with the front of the casing, each container having an opening registerable with the said slot in said partition when the container is closed; oppositely acting levers oscillative on a common axis in the slot of 95 said partition, each lever having at its upper part a hook member and a guard member, the hook member of each lever effective to lock one container and the guard of the other lever effective to guard against release 100 of the engaged hook. 105

In witness whereof we have hereunto signed our names at Springfield, Sangamon county, Illinois, this 19th day of August 1925.

HAL G. BAKER.
JOHN R. MOORE.
